B. F. Gold,

Lathing Machine.

NO. 11423.

Patented Aug 1. 1854.

Fig. 1.

Fig. 2.

UNITED STATES PATENT OFFICE.

B. F. GOLD, OF NEW HAVEN, CONNECTICUT.

LATHING BUILDINGS.

Specification of Letters Patent No. 11,423, dated August 1, 1854.

To all whom it may concern:

Be it known that I, B. F. GOLD, of New Haven, in the county of New Haven and State of Connecticut, have invented a new 5 and Improved Mode of Lathing Preparatory to Plastering; and I do hereby declare that the following is a full and exact description thereof, reference being had to the accompanying drawings and to the letters 10 of reference marked thereon.

The nature of my invention consists in providing a frame of a capacity and construction suitable to receive and apply, to a wall or ceiling, a break of lath at once; 15 and, in connection with the frame, to make any required and equal spaces between the lath, by means of spacing-pins, placed on rods, or, in the grooves of rods or ways, so that the spaces may be made larger or 20 smaller by either turning the rods or ways, on a pivot, the length of pins standing crosswise of rods, or, by turning the pins only, by arms affixed to them.

To enable others skilled in the art to 25 make and use my invention, I will proceed to describe its construction and operation.

Section 1: To cover all spaces on a wall down to a foot in width, I make and use three frames, which may be made of wood 30 or iron. If made of wood the slats composing the frame, should have their edges, or greatest depth, presented toward the lath, that the weight of a frameful of lath, may not bend the frame. Wrought-iron rods, $\frac{1}{16}$ 35 inch square, are better than wood, as security against breaking, and best adapted for use. The frame designed for lath 4 feet long need be but about 30 inches long, allowing the lath to project at each end 9 40 inches. The width of frames, should be about two feet, or rather their height, as they are applied to the wall. The 2nd, or middle sized frame, need be but 20 inches, for lath 32 inches long. The 3rd size, or 45 that designed for lath from 12 to 20 inches long, will be but 10 inches.

Sec. 2: The various frames must be of equal height or width. This will insure a 50 level of each break. The stationary pins P, P, Figure 1, make equal spaces between breaks, which are separated by them, and, against which, the lath are spread to H, H, the gages. To commence lathing, I first nail a lath at the floor or base of the wall, 55 that the points of the binder I at K, or a button at rear of the frame, in the same

places, when the binder is not used may project over and back of the lath, and hold that side of the frame to the wall. The pins for giving spaces between the lath, if made 60 about $\frac{1}{2}$ inch high, and, the largest or jutting at the top, will need no binder to hold the lath to the frame, as, by turning the pins by the arms n, Fig. 1, the spaces are increased, and, the lath spread on the frame, until 65 they are made to touch and press, against the gages H, H, and equally against the tops or juts of the pins, or, against the pins below the juts. This will hold them to the frame, without a binder, or, the binder, I, 70 Fig. 1. To prevent pinching, a reverse motion of the arms or rods must be made, to take the frame from the wall. The pins for making spaces may be crosswise of the rods and shortest, when turned by arms. 75 Their thickness, may be about $\frac{1}{16}$ inch except at the top or juts, where they should jut about $\frac{1}{2}$ inch each side, gradually, commencing $\frac{1}{16}$ below the top, and curve outward to the top. The gages, are always to 80 be placed at equal distances from the front of the frame, that they, and the lath, may be kept level. The gages H, H, should be $\frac{1}{4}$ inch thick, and should rise as high as the top of the lath, when placed on the frame. 85 The number and width of breaks, which may be put upon a wall, or ceiling, should be ascertained, before commencing lathing, that the gages H, H, which govern the width of breaks, may not be moved while lathing 90 any given space.

Section 3: The sustainer, letter K, at each end of the same, Fig. 1, turns on a pivot or bolt at the center of the cross-piece b. The cutters L, L, are placed in slots of the swivel 95 M, that they may cut and hold to studs or joist, which are at unequal distances apart; as the cutters are moved nearer together, or, farther apart, and fastened by thumb screws T, T, Fig. 1. The swivel M, turns on a 100 pivot at the front end of sustainer. The cutters are steel, the swivel, malleable iron; that a lip may be cast each side of the cutters. Cutters should reach the studs when the swivel stands obliquely, so that a blow 105 of the lathing hatchet at one end of swivel, will drive the cutters easily into studs or joist, the end of cutters being thin and rounding. The cutters in this manner, hold the front of the frame to the wall. On the 110 opposite side or rear of the frame, a pin in binder I is made to enter a hole in sustainer

K, and the branches of the binder to pass each side of it, and back of the lath, holding that side to the wall. A pin in the front end of the binder, is by a spiral spring, in like manner, thrown under staple S, to bind the lath to the frame. To remove the frame from the wall, (the lath having been nailed to the wall in the usual way,) the thumb-piece α , Fig. 1, is made to press back the pin, and the binder is liberated and the frame taken from the walls after removing the cutters by a blow of the hatchet.

Section 4: In Fig. 1, the arms n , n , are riveted to the spacing pins, below the slide j , through which they pass, and move with the pins, in the grooves of the rods. The arms are turned by the grooved rods E, E, the ends of the arms entering the grooves.

To turn the spacing pins, the rods E, E, are drawn toward the front of the frame by thumbpieces α , α , Fig. 1, but, they may be moved more easily, by a lever on the top of the frame at z , z , which might be the pivots, the lever and rod to be connected by a coupling link. It will be seen, that levers, must turn inward or outward, according to the place of their fulcrums or pivots. This is not in the drawings, as a suggestion was deemed sufficient.

Fig. 1, d , d , represent the grooved rods, in which the slides are made to move with the pins. g , g , are guards, (in which are slots, for gages H, H,) used as protection of the arms, and bottom of the pins. They sustain the arms at their ends, and hold them in their grooves. They may be of sheet brass, iron, or of wood. The end pieces R, R, of the frame, are detached at a , a , to shorten the frame, instead of using a shorter frame.

In Fig. 4, the arm, is secured to one end of the pin, that a slip of brass or tin, may be soldered to the lower side of grooved rods, to hold them in their places firmly, allowing the slides to move in the grooves above the slips, without obstruction; and, was designed as an improved modification of the manner of attaching arms to pins. The pin, is riveted to the slide, and, set back, that it may move easily.

Section 5: To fill the lathing frame, it should be placed on a portable filling-frame, having 2 legs and 2 arms, an arm and a leg hinged together, and placed 3 feet apart, connected, by suitable girts and braces, arms 20 inches long, and legs 22 inches. The legs standing perpendicular, and arms hori-

zontal, that the ymay be fastened to studs, by means of hooks or dogs which may slide on a wire, extending from arm to arm, and fastened to them one inch from their ends. 60 A girt of wood should be secured to the top, and even with the ends of arms, so as to touch against the studs, and rest upon the dogs when they are fastened, the points of dogs facing each other as they enter the 65 studs.

There should be a gage of wood at either end of the filling frame, that the ends of lath may be even, as the lathing frame is placed on the filling frame to be filled. This 70 gage, against which the ends of lath are made to touch, should be about 2 feet long, and one inch and a half wide, or, that height above the arms of the filling frame.

The hinges, uniting the arms and legs, 75 make it easily portable. One of this description I have used some months since, and found it a useful and essential appendage.

There should be 12 spacing-pins on slides, 80 which move in grooved rods, at each end of the frame, which will make the number proper for a break of lath. The gages H, H, Fig. 1, may be placed at such distance from the front of the frame, as a break of lath 85 may require. The mode of making the spaces between lath is, by turning the pins obliquely across the rods, by arms, as in Fig. 1.

What I claim as my invention, as new in 90 application, and for which I desire to secure Letters Patent, are—

1. The mode of making spaces between lath by turning spacing-pins, which are attached to slides, as specified, the mode of 95 turning being by arms n , n , Fig. 1.

2. Stationary spacing pins as P, P, Fig. 1, to make equal spaces between breaks of lath, and, as a permanent footing against which, lath are spread to touch the gages H, H, 100 Fig. 1. The spacing-pins are on the rear of the frames.

3. The gages H, H, Fig. 1, which are placed in front of any required number of lath, and, are requisite to control the width 105 of breaks, the spaces between lath, and, to keep them level.

B. F. GOLD.

Witnesses:
